SHOE SEWING MACHINES

Alfred S. Clark, Beverly, Mass., assignor to United Shoe Machinery Corporation, Flemington, N. J., a corporation of New Jersey

Application January 9, 1952, Serial No. 265,660

11 Claims. (Cl. 112—47)

The present invention relates to improvements in shoe sewing machines, more particularly of the type disclosed in United States Letters Patent No. 2,542,993, granted February 27, 1951, upon application of the present inventor, in which a shoe upper, a sock lining attached to a rabbeted platform sole and a platform wrapper or sole binding strip are sewn together with a seam passing through all the parts except the platform sole, the exposed threads of the seam appearing on the wrapper strip and on the sock lining within the rabbet of the sole.

The machine to which the construction of the prior patent is applied is a curved hook needle shoe outsole stitching machine intended for operation upon heavy sole material, the machine being provided with a curved hook needle and a curved work penetrating and feeding awl. The type of work intended to be operated upon by that machine as originally designed is of such thickness and rigidity that it is essential to employ an awl to form a perforation in the work for the subsequent passage of the needle and to feed the work. With rigid work the awl makes an effective work feeding instrument. However, the type of work on which the machines of both the prior patent and the present invention are intended to operate may include relatively light flimsy material such as cotton drill or other loosely woven fabric. In order to avoid cutting or fraying excessively the fibers in fabric so as to cause large numbers of loose projecting ends in the fibers or other injury to the strength of the fabric, it is desirable to utilize a work penetrating instrument of much smaller gage than that employed in the patented machine. With the use of a small gage awl, the awl loses a substantial proportion of its stiffness and so is subject to greater flexure during work feeding movements with the result that stitches of irregular length may be formed or the work may be more difficult to control in its movement through the machine.

The work operated upon by the illustrated machine also is composed of flat sheet materials cut into blank shoe upper and sole forms with edges of different curvatures shaped to predetermined patterns. The sole form comprises a thickness of resilient platform material with the sock lining attached thereto. In addition, the platform material is rabbeted along its edge to approximately one half of its thickness beneath the sock lining. The upper and sock lining projecting from the platform material are then sewed together with their edges of different curvatures in register, the patterns by which the parts are cut being such that the shape of the shoe is created during the sewing operation, no last being employed. It is because of the rabbet in the sole that a curved needle machine is required, particularly because it is essential to sew the upper to the sock lining through that portion of the lining which projects from the sole above the rabbet without including the sole material below the rabbet. To accomplish proper register of differently curved edges on the parts, much skillful and attentive manipulation is required of the operator in presenting the parts to the machine.

2

A further purpose of both the prior and present machines is to attach a strip of wrapper or sole edge covering material also composed of light flimsy leather or composition fabric to the shoe parts being operated upon.

5 The attachment of a curved wrapper strip, together with the task of bringing the upper and sock lining edges into register, ordinarily would impose an almost insuperable burden on the operator. The operation heretofore has been performed so slowly that the expense of a specially designed machine may not be justified.

To relieve the burden on the operator of presenting all the parts in proper register to the machine of the prior patent, it is equipped with a feeder for assisting the operator in guiding the wrapper strip toward the sewing point 15 so that he may give his full attention to the proper registration of the upper and sock lining edges only. The patented feeder comprises flat metal plates formed with toothed elements at their ends yieldingly engaging the wrapper strip. Such an arrangement acts to feed the 20 strip effectively in a straight line and provides beneficial results when the wrapper strip itself is composed entirely of straight strip material. If, however, the strip is of variable width and is curved in a manner to conform it- 25 self with a relatively high wedge heel on a shoe, such a feeder will not maintain the edge of the wrapper strip in proper register with the other parts of the shoe and the advantage of the feeder in large measure fails.

It is accordingly an object of the present invention to provide an improved sewing machine for use in the manufacture of rabbeted platform type shoes in which the manipulation of the work by the operator is facilitated to such an extent that the overhead expense and upkeep of a special machine designed for the purpose is economically feasible, the saving in speed of presenting the 30 parts to the machine and the quality or workmanship obtainable justifying the effort directed toward machine improvements. A further object is to improve the work feeding action of a sewing machine adapted primarily for operation upon a rabbeted platform type of shoe in which the presentation of the shoe to the machine will require less skill and ability on the part of the operator than heretofore and in which the stitches of a seam connecting the upper to the sock lining will have greater holding power and will be inserted without any tendency to 35 reduce the strength of the parts by fraying or improper spacing of stitches either from each other or from the edges of the parts.

A machine embodying the present invention is provided with a curved needle and a work support disposed with its work engaging surface at an angle to that part of the needle path along which the needle engages the work to enable the needle to enter and emerge from a shoe upper and sock lining attached to the upper surface of a rabbeted platform sole without penetrating the sole, in which machine the work is secured and fed by two separate clamps comprising a non-feeding presser foot and a feeding presser foot cooperating with non-feeding and feeding gage members arranged to fit within the rabbet of the platform sole beneath the upper and sock lining. By the use of separate clamps, one of which is stationary 40 and the other of which feeds the parts operated upon, there is no possibility of displacement of the parts relatively to each other as with a machine having a work feeding awl.

65 This and other features of the invention are embodied in the devices, combinations and arrangements of parts hereinafter described and claimed, the advantages of which will readily be understood from the following detailed specification taken in connection with the accompanying drawings, in which

Fig. 26 is a sectional view on an enlarged scale taken along the line XXVI-XXVI of Fig. 25.

The apparatus illustrated in the drawings is a curved eye-pointed needle lockstitch sewing machine of the type disclosed in inventor's patent above identified which machine is intended to operate upon a shoe similar to that described in United States Letters Patent No. 2,546,152, granted March 27, 1951, upon application of J. D. Chandler. The shoe disclosed in these patents is of the platform type in which a sock lining is attached to a rabbeted platform sole above the rabbet and the edges of a pre-cut upper are secured to the sock lining by a

seam inserted along the inner face of the rabbet without including the platform sole. For binding the edge of the platform sole, a wrapper or platform cover strip also is attached to the edges of the upper and sock lining so that the strip may be lasted over the edges of the parts into overlapping relation with the bottom of the platform sole.

The machine of inventor's prior patent is effective for sewing the parts of a shoe thus constructed when relatively flat low heel shoes of uniform shape with no abrupt curvatures are operated upon, a straight wrapper or cover strip being effective for binding the edges in such shoes. If an attempt is made, however, to sew high heel shoes having abrupt lengthwise curvatures along the edges of the parts, the stitch forming and work feeding devices of that machine do not cooperate with each other effectively to produce the best results. Difficulty frequently is encountered in sewing high heel shoes in proper presentation of the upper to the sock lining while at the same time flexing the platform sole to which the sock lining is attached with a sufficient degree of curvature to create the desired shape of the shoe. This difficulty is most troublesome when sewing along the inside shank of a shoe, the parts tending to pull loose from their operating position in the machine and to become so displaced that the needle in the machine fails to penetrate the parts at the proper points. This difficulty is partially the result of the manner in which the prior machine feeds the parts operated upon through the use of a work feeding awl.

The prior patented machine is an adaptation of a well-known form of sole sewing machine, similar to that disclosed in United States Letters Patent No. 473,870, granted April 26, 1892, in the names of French and Meyer and is equipped with a stationary clamp comprising a presser foot and a rabbet gage, the parts being retained upon a work guiding support. During feeding movements, the clamping action on the shoe parts is released so that the awl is the only instrument which retains them from displacement. Since there is a strong tendency for the edges of the shoe parts to separate, the awl alone is insufficient to prevent such separation and displacement.

According to an important feature of the present invention a completely new machine is provided which is constructed in a manner most effective for operation upon a rabbeted platform shoe with novel work clamping members in the machine acting to prevent displacement of the parts operated upon both during feed of the work and during formation of stitches. Thus, the use of a single work penetrating instrument such as an awl or similar work piercing instrument alone is no longer relied upon exclusively to feed and to retain the shoe operated upon from displacement during work feed, the other parts of the machine, including the stitch forming devices necessary to insert a seam connecting the sock lining and upper of a rabbeted platform shoe, cooperating effectively with the clamping and feeding devices.

Referring more particularly to Figs. 22 to 25, inclusive, of the drawings, the shoe operated upon comprises a semi-rigid platform sole 2 cut from a quarter inch layer of granulated cork composition and a sock lining 4 of flexible cotton drill material attached to the upper surface of the platform sole with its edges in registry with those of the sole, an upper 6 and a wrapper strip having a toe part 8 and a heel part 10 all connected together with stitches of a seam extending about the edges of the parts and intersecting them, with the exception of the platform sole. The toe part 8 is straight but the heel part 10 is of variable width and curvature to conform with a high heel of a high arch shoe. The platform sole directly beneath the sock lining is formed with a groove or rabbet 12 into which the seam allowances of the parts along their edges are folded when the wrapper strip is lasted about the platform sole, the rigidity of the platform sole

along its edges insuring proper outline configuration of the shoe during insertion of the connecting seam. The improvement obtained in outline configuration of a shoe by the use of a semi-rigid platform sole, however, raises further problems if an attempt is made to construct a style of shoe having high heels. The rigidity of the sole which insures the improved outline resists flexure essential to bringing the edges of the attached sock lining readily into register with the edges of the upper. Since the resistance to flexure in the sole is met during the sewing operation, sufficient force must be applied to the parts in advance of and at the sewing point in the machine itself to offset this resistance.

As illustrated in Fig. 23, the right side of the vamp portion in the upper 6 first is secured to the flexible edge 15 of the sock lining 4 overlying the rabbet 12 in the platform sole by a seam 14 while presenting the differently curved edges of the parts in register, starting at the toe, as indicated by the arrow 5. The sewing operation is interrupted when the shank of the shoe is reached, the parts at this time being slightly distorted from their flat blank shape (Fig. 23). The upper, being the more flexible part, is caused to project upwardly from the platform sole with practically no distortion of the sole itself. At the forward part of the shank one end of the curved heel part 10 for the variable width wrapper strip is applied then to the upper, starting at the head of the arrow 11.

To assist in locating the parts, the sock lining is formed with several pairs of projections or other marks 16, 18, 20 and 22, one of a pair at each side of the sole. The projections 16 indicate the proper position for two points 17 at the toe end of the upper. The projections 18 indicate the stopping positions for the forepart sewing operation so that the wrapper strip may be applied. The projections 20 indicate the proper position for applying the heel part of the wrapper strip, and the projections 22 the location of the heel ends of the upper.

After applying the curved heel part 10 to the shoe upper a seam 23 is continued from the seam 14 along the edges of the registering parts entirely around the shoe. As soon as the heel end of the platform sole is reached, a substantial lengthwise curvature must be imparted to the sole to bring it into the shape of Fig. 24. In bending the sole into the curved shape of Fig. 24, substantial resistance is met in flexing the parts at the sewing point. Sufficient force must accordingly be applied manually to the shoe parts to overcome this flexing resistance. In applying the flexing force to the parts tension is imparted to those portions of the seams already inserted, particularly about the point of sewing operations so that unless a secure grip is maintained on all three parts, both by the operator as well as by the machine, the edges will be displaced, causing irregularities in the form of the completed shoe. As appears in Fig. 25, the completely sewed shoe has a still greater curvature along the bottom surface of its platform sole than the incompletely shoe of Fig. 24, the curvature being the result of stress set up in the parts during insertion of the stitches as a result of bringing the differently curved edges of the parts into register.

In inventor's prior patented machine if an attempt is made to sew a high heel shoe with a curvature of the sole bottom similar to that shown in Fig. 25, it is extremely difficult to maintain the parts in register along their edges during the sewing operation. This difficulty results at least in part from the feeding action produced by the awl of that machine. As the shoe is being fed the clamping action of the presser foot is released and the shoe parts tend to separate, moving lengthwise along the awl so that when they are again reclamped the perforations in the shoe parts formed by the awl do not line up with the needle. Unless substantial effort is made to overcome this difficulty each stitch inserted will be displaced from the previous one in a cumulative manner

until the seam eventually fails to intersect one or more of the shoe parts.

In order to reduce the effort expended by a sewing machine operator while connecting the parts of a rabbed platform type shoe, the form of which is created during stitching operations, the machine of the present invention is provided with a primary stationary or non-feeding work clamp and a supplementary feeding clamp having cooperating members, consisting in each case of a presser foot and a gage arranged for entry into the rabbet of the platform sole to guide the location of the seam. For supporting the parts operated upon against the thrust of the sewing needle to insure that the parts as they are presented to the machine will be disposed at the proper angle so that the needle will enter the upper and sock lining and emerge therefrom adjacent to the edge of the sole from the rabbet of the sole, a work support 24 is provided having an extended surface beneath the work clamps. With such arrangement the parts operated upon are presented at the proper angle and are compressed together at the sewing point by a continuous grip of the clamps acting alternately without any interval of complete release. For this purpose the clamps are actuated by a convenient mechanism for insuring that one clamp will release the shoe only after the other has secured the parts from separation. Preferably, the work feeding clamp is mounted on a carrier movable in the line of feed and the curved needle, which is eye-pointed as indicated at 26, has a supporting stud 28 also mounted on the carrier.

As best shown in Figs. 5, 7, 8, 9 and 21, the work feed carrier comprises a swinging frame 30 rotatably mounted on a spindle 32 secured in vertical position within a portion of the machine frame by clamp screws 34 (Figs. 5 and 9). The spindle projects above and below the portion of the frame in which it is mounted and enters loosely into bearing portions of a yoke in the carrier 30. The upper end of the carrier has a forwardly projecting arm to which is bolted on its forward side at 36, a plate 38, the forward end 40 of which forms the supplementary work feeding rabbet gage. The plate 38 has fixed within it at its central portion the forward end of the needle supporting stud 28, projecting through a needle segment 42 and forming a pivot for the needle segment. The rearward end of the stud 28 is supported in a plate 44 also clamped to the carrier by the bolts 36, the stud being supported at either end by the plate 38 or 44.

Cooperating with the work feeding rabbet gage 40 is the supplementary feeding presser foot 46 comprising a T-shaped lever having a presser foot formation at its left end and an integral stud 48 (Figs. 5 and 8) at its right end rotatably mounted in a lug portion of the carrier 30. A downwardly extending portion of the supplementary presser foot lever has integrally secured to it a stud 50 connected to presser foot actuating mechanism to be described hereinafter. The rabbet gage 40 and the presser foot 46 together form the work feeding clamp for gripping and feeding the work while the work is presented at the proper angle to that part of the needle path engaging it so that the needle will enter the upper 6 and the sock lining 4 of a shoe and emerge from the rabbet of the platform sole 2 without intersecting the lower outer corner of the rabbet at the edge of the sole.

The non-feeding work clamp is best illustrated in Figs. 6, 7 and 21 and comprises a horizontal arm forming the non-feeding presser foot, indicated at 52, at its left end and provided with an integral stud 54 at its right end rotatable in a bearing lug on a bracket 56 bolted to an up-standing pedestal 57 of the main frame (see Fig. 7). Cooperating with the non-feeding presser foot 52 is the non-feeding rabbet gage comprising an angularly bent plate 58 secured by bolts 59 to the frame of the machine. The rabbet gages are disposed to fit within the rabbet of a platform sole beneath the upper and sock lining.

along those portions lying between the presser feet and the work support 24. The arrangement is such that both the feeding and non-feeding rabbet gages 40 and 58 (see Fig. 4) enter into the rabbet 12 of a shoe being sewn while the platform sole 2 rests on the work support 24 and the presser feet 46 and 52 alternately engage and clamp the upper and sock lining of a shoe along the seam allowance. The needle acts to enter the work while the feeding presser foot clamps it and to move with the work during feeding operations. During feeding movement of the work the feeding presser foot 46 engages the work ahead of the clamping position of the non-feeding clamp and moves toward the non-feeding clamp so that the clamping position of the feeding clamp is brought as close as possible to that of the non-feeding clamp. In this way possibility of slippage between the parts being operated upon is reduced to a minimum.

The mechanism for actuating the work clamping presser feet alternately so that one presser foot will not release its grip on the work until after the other presser foot has gripped the work securely against its rabbet gage comprises a sleeve 60 (see Figs. 5 and 6) surrounding the stud 50 and having a spherical outer surface fitting within a spherical socket at the upper end of a link 62. The lower end of the link 62 also is formed with a spherical socket to receive a ball headed stud 64 clamped to one arm of a rocking lever 66. The lever 66 is rotatable on a pin 68 secured to a bifurcated end of a U-shaped radius arm 70, the lever 66 being located between the bifurcated portions of the arm. The arm 70 is also secured to a shaft 72 extending rearwardly of the machine and having supporting bearings 74 and 76 in the machine frame.

The non-feeding presser foot is connected to the rocking lever 66 through a rearwardly extending arm of the lever which has secured to it a ball headed stud 78 engaging a socket at the lower end of a link 82. The upper end of the link 82 has a similar socket engaged with a ball headed stud 84 secured in turn to a downwardly extending lug on the arm forming the presser foot 52. For rocking the lever 66 a downwardly extending arm thereof has an opening in which is secured by a clamp screw 85 an eccentric portion of an adjustable eccentric stud 86 passing loosely through the forked ends of an eccentric strap 88. The eccentric strap 88 surrounds an eccentric 90 fixed to a sewing shaft 92 rotatable in three bearings 94 on the machine frame (see Fig. 7).

To cause the presser feet to engage the work alternately a rearward projection of the pin 68 passing through the lever 66 has connected to it the upper end of a tension spring 98, the lower end of which is made fast to a pin 100 on the machine frame. The pin 68 engages the rocking lever 66 midway between the studs 64 and 78 so that equal forces are applied by the non-feeding presser foot 52 in clamping the work and by the feeding presser foot 46.

In operation the presser foot mechanism oscillates the rocking lever 66 through the eccentric 90, first in one direction and then in the other. The rocking lever swings first about the stud 64 and then about the stud 78 depending upon which of the presser feet are in engagement with the work. Whichever presser foot engages the work resistance is provided to the action of the spring 98 to enable the other presser foot to be raised and again lowered into engagement with the work. As soon as a presser foot engages the work continued movement of the rocking lever transfers the force of the spring from the presser foot already engaging the work to that which just engaged it, both presser feet engaging the work for a short interval so that likelihood of displacement of the work parts, one from another, is avoided.

By reason of the needle stud mounting on the feed carrier 30 the needle while engaging the work during each sewing cycle moves with the feeding clamp a stitch length to a position close to the non-feeding presser foot.

An additional purchase on the shoe is thus obtained in a manner to prevent any possibility of dislocation either vertically or horizontally, the use of a curved needle and the approach of the needle supporting segment into close proximity with the work while the needle engages it (Figs. 12 and 13) adding to the rigidity of the needle and the security with which the work is retained in the machine against displacement.

To actuate the feed carrier 30 it is provided with a rearwardly extending slotted arm, best shown in Figs. 8, 9 and 21. Within the slot of the arm on the feed carrier is slidably engaged a rectangular block 102 rotatable on a pin 104 having an enlarged integral head. The head of the pin 104 has a transverse threaded passage within which is engaged an adjusting screw 106. The head on the pin 104 is supported within a guideway formed in a block 108 rotatable on a vertical shaft 110 clamped within a boss portion of the machine frame. At the ends of the guideway in the block 108 are clamped a pair of plates 112 having perforations to receive the ends of the adjusting screw 106, the adjusting screw having a knurled head for convenience in rotation. To prevent displacement of the adjusting screw 106 from the plates 112, one end of the screw carries a collar 114 and the other end beneath the knurled head has a lock nut 116. Rotation of the adjusting screw moves the pin 104 and the block 102 in the slot of the arm on the feed carrier 30, varying the effective length of the arm, to provide means for adjusting the length of each stitch. To impart movement to the block 102 the pin 104 is located eccentrically to the shaft 110 and the block 108 is oscillated through connections with the sewing shaft of the machine.

The connections between the main sewing shaft 92 and the block 108 for actuating the feed carrier comprise a stud 118 on the block having a spherical head engaged by a socket at one end of a link 120 having at its other end a strap portion surrounding an eccentric 122 (see Fig. 7). The outer surface of the eccentric 122 has a spherical contour to fit within a corresponding surface of the strap.

To provide convenient means for raising both presser feet simultaneously from clamping engagement with the work, a mid-portion of the shaft 72 (see Figs. 5 and 8) has clamped to it the hub of an arm 124 disposed at its free end above a threaded cap 126 adjustably secured to the upper threaded end of a treadle rod 128. Whenever the treadle rod is raised it engages the arm 124, rocking the shaft 72 and swinging the radius arm 70 in a clockwise direction. Swinging the radius arm 70 clockwise raises the pin 68 and the rocking lever 66 bodily against the tension of the spring 98, causing both presser feet to disengage the work regardless of the stopping position of the machine.

In order to provide reinforcement for the needle 26 during its feeding movement while engaging the work so that a relatively thin gage needle may be employed, the needle passes through an opening in a needle guide frame 130 close to the upper surface of the work and upon emergence from the rabbet of the platform sole being sewn the needle is reinforced by one side of the supplementary feeding rabbet gage 40 and by a surface on a loop spreader 132 (see Fig. 5) acting to transfer each loop of thread carried by the needle to a shuttle 134. Thus, the needle is reinforced in two directions along the line of feed in the machine both above and below the work, the loop spreader 132 acting at the opposite side of the needle from the rabbet gage 40.

The needle guide frame 130 comprises a continuous bar arranged in a slightly inclined position and provided with a rearward projection 136 (see Figs. 12 to 20, inclusive) clamped within an opening in an upwardly projecting portion of the plate 38 on the feed carrier. The needle guide frame also is strengthened in its mounting by a brace bar 138 extending from the frame to a screw 140 threaded into an upwardly projecting portion of the

feed carrier. To clamp the needle guide frame in the feed carrier the rearward projection 136 thereof is engaged by a set screw 142 threaded in the carrier, the arrangement being such that the projection 136 may be slidably adjusted in the plate 38 to bring a needle receiving opening 144 in the guide into accurate alignment with the needle.

Referring to Fig. 18, the guide frame 130 has its needle receiving opening 144 formed to act most efficiently in stiffening the needle while avoiding the possibility of abrading unnecessarily or otherwise injuring the thread carried by the needle. The opening 144 is shown as approximately triangular in shape, one side of the triangle acting to reinforce the needle along its inner concave surface while the other two sides of the triangle act on the needle along its outer surfaces, leaving spaces at the inner corners of the triangle to receive the thread as it passes transversely to the length of the needle from the needle eye. With the needle opening of triangular shape reinforcement is provided in any direction transversely of the length of the needle 26, the opening being a sliding fit for the size of the needle employed.

Within the rabbet of the platform sole 2 the reinforcement of the needle by the rabbet gage 40 is accomplished by a flat end of the gage formed with its edges well rounded so as not to injure the thread carried by the needle. At the side of the needle opposite the rabbet gage 40 the needle, when in its maximum work penetrating position, comes into contact with a surface 146 (see Figs. 13 and 16) on the spreader 132. The surface 146 is formed on a downwardly projecting lug portion of the spreader. Forwardly of the surface 146 is the hook of the spreader which enters the loop carried by the needle, as best shown in Figs. 12 and 13. The surface 146 not only reinforces the needle but it serves as a convenient means for locating the hook of the spreader properly with relation to the needle to cause the hook to enter the needle loop with certainty.

The loop spreader 132 comprises a rearwardly projecting bar having projecting from it near its forward end a pin 148 rotatable in the lower end of the radius arm 150. The radius arm swings on the screw 140. At its right end the loop spreader bar is slotted, as best shown in Fig. 9, and engages within its slot a split block 152 forming a part of the spreader actuating mechanism.

The loop spreader actuating mechanism operates the spreader in timed relation to the work penetrating stroke of the needle 26 and, in order to transfer each loop of thread carried by the needle with rapidity to the shuttle, the spreader is driven in a more or less elliptical path 153 (Fig. 9) twice for each oscillation of the needle, one transition of the spreader taking place idly without engaging the needle or thread. The spreader mechanism includes a split block 152 having a pin 154 passing through it and the fork ends of the spreader bar. The parts of the split block 152 are recessed to form a socket for the spherical head of a crank pin 156 supported on an arm 158 (see Figs. 5, 8 and 9) secured to a horizontal shaft 160 rotating in the upper end of the pedestal 57 on the machine frame. The pedestal 57 is hollow and forms an enclosure with the bracket 56 for a pair of bevel gears 162, 164 (Fig. 7) on the shaft 160 and on a vertical connecting shaft 166, respectively. The connecting shaft 166 has bearings in the pedestal 57 and at its lower end carries a bevel gear 168 meshing with a similar gear 170 having twice the number of teeth on the main sewing shaft 92, the ratio of teeth on the gears 168, 170 providing the two to one speed ratio for the loop spreader. The split block 152 connecting the crank pin 156 with the loop spreader enables the rearward end of the loop spreader bar to move laterally in accordance with the feeding movements of the bar and its radius arm 150 as it is shifted by the feed carrier.

For oscillating the needle, mechanism actuated by the

main sewing shaft 92 is provided. This mechanism includes a counterweighted crank 172 the pin of which has a spherical surface engaged by a socket at one end of a pitman 174. The other end of the pitman is similarly connected to a pin 176 on one arm of a bell crank 178. The bell crank 178 is rotatable on a stud 180 supported at its ends in a pair of lugs projecting from the machine frame. The other arm of the bell crank 178 carries a ball headed pin 182 received within the socket of an adjustable link 184 similarly connected to a pin 186 secured to the needle segment 42.

The shuttle 134 is similar in its construction to shuttles of conventional form and includes within it a stationary thread case 188 having a circumferential rib rotatable in a guideway within the shuttle. The shuttle is rotated twice for each oscillation of the needle and is provided with special means for avoiding interference by the loop spreader with each loop of needle thread as it is carried about the thread case.

Referring more particularly to Figs. 12 to 20, inclusive, the needle is illustrated in its maximum work penetrating position in Figs. 12 and 13. In this position it is engaged by the loop spreader 132, the hook thereon being shown as it enters the loop of needle thread. The spreader is then retracted from the needle and the needle begins to rise to the position of Figs. 14 and 15, the beak of the shuttle then entering the spread needle loop. As the needle continues to retract from the work the shuttle begins to carry the loop about the thread case to the position of Figs. 16 and 17. However, by the time the loop is carried nearly about the thread case to the position of Figs. 19 and 20, the loop spreader again approaches the path of the needle to a position where possible interference with the loop carried by the shuttle may occur.

To avoid interference of the loop spreader with the loop carried by the shuttle, the shuttle is formed with a detaining arm 192 located with relation to the loop entering beak in a position displaced along the rotary axis of the shuttle and angularly about the shuttle axis to move the loop carried by the shuttle out of the range of the spreader hook during its idle actuation. The action of the detaining arm is clearly illustrated in Fig. 19, which shows the rearward leg of the needle loop carried by the shuttle deflected laterally out of the path of the loop spreader. The detaining arm also prevents engagement of the loop of needle thread carried by the shuttle about the thread case from being engaged by the shuttle beak a second time as the loop is being contracted by the stitch forming devices.

To drive the shuttle it is secured to the forward end of a horizontal shaft 194 rotatable in bearings in the machine frame and the shaft carries a spur gear 196, best shown in Fig. 9. The spur gear 196 meshes with an idler 198, in turn meshing with a driver 200. The driver 200 has twice as many teeth as the spur gear 196 and consequently the shuttle shaft is driven two revolutions for each rotation of the driver 200, the driver 200 being secured to the main sewing shaft 92.

To retain the thread case 188 against rotation with the shuttle, a notch in the thread case is engaged by a retainer arm 202 projecting upwardly and rearwardly from a cover plate 204 for the shuttle. The cover plate 204 is secured to a horizontal hinge pin 206 rotatably mounted at its ends in the machine frame. For convenience in access to the thread case the work support 24 also is mounted on the cover plate 204 so that it swings outwardly of the machine with the cover plate. To lock the cover plate in place, it has pivoted on it a catch 205 (Fig. 3) arranged to engage a slot in the machine frame. Raising the catch 205 enables the cover plate to be swung outwardly to provide suitable access for shuttle thread replacement and adjustments.

The other stitch forming devices of the machine include a takeup and a thread tension. The takeup con-

sists of two arms 208, 210 rotatable about fixed axes 212 and 214, respectively. The axis 212 consists of a screw threaded into a bracket 216 clamped to the machine frame and the axis 214 comprises a stud carried by the bracket 56. The arm 210 is adjustably connected to a bell crank 218 which rotates on the axis 214. The bell crank has a counter weight portion to which is fixed an angle plate 220 having a threaded opening to receive a screw 222. The screw 222 forms a pivot for a link 224 also pivotally connected to the takeup arm 208. By reason of the link 224 the arm 208 moves in an opposite direction from the takeup arm 210. For actuating the takeup arms the bell crank 218 is pivotally connected to a link 226, in turn connected to a lever comprising an arm 228 of a pitman 230. The juncture of the arm and pitman has passing through it a pin 232 (see Fig. 10). The pin 232 also passes through a radius arm 234 rotating on a fixed stud 236, the pitman 230 surrounding a crank 238 on the main sewing shaft 92.

To assist the takeup action and to provide rapid movement of the thread at the proper time to set each stitch in the work, the takeup arm 208 moves downwardly past the upper end of a plate 240 fixed to the frame of the machine (see particularly Fig. 11). The plate 240 is notched at its upper end to prevent escape of the thread as the takeup arm 208 swings downwardly, the thread being deflected between a guide eye 242 at the upper end of the arm 208 and a perforated guide pin 244 secured to the machine frame from which the thread passes toward the sewing point. From the guide pin 244 the thread is led through a vertical passage in a pin 246 secured to the upstanding projection of the plate 38 on the feed carrier and downwardly through the eye of the needle. The takeup arms 208 and 210 act with a scissors motion, swinging in opposite directions simultaneously to take up or release the thread running between their respective guide eyes. From the guide eye in the arm 210 the thread runs through a loop 248 mounted on a support plate 250 bolted to the machine frame. The plate 250 has a circular portion on which the thread tension comprising a pair of disks 252 (Figs. 8 and 10) is mounted. The tension disks are pressed together by a spring 254 and their action regulated by a thumb nut 256 threaded on a central disk supporting stud 258 secured to the plate 250. From tension disks the thread passes through an opening in a stationary pin 259 and extends to a thread supply (not shown).

To cause the tension on the thread to be released when the presser feet are raised so that the sewn shoe may readily be disengaged from the machine, the upper disk 252 has a lateral projection to which is secured a pin 260 slidably mounted in the plate 250. When the presser feet are raised, an arm 261 secured to the shaft 72 engages the lower end of the pin 260 and releases the tension on the thread.

The main sewing shaft 92 carries at its rearward end a hand wheel 262 formed with an integral pulley to receive a driving belt 263 passing over the driver of a power transmitting mechanism (not shown) controlled by the operator through a conventional foot treadle.

To avoid the difficulties met in the awl feed arrangement of the machine of inventor's prior patent so that platform cover strips may be sewed to relatively high heel shoes, the illustrated machine is provided with a cover strip guide of particularly advantageous construction, especially when employed with platform cover strips having both varying widths and curvatures. As will be noted in connection with Fig. 22, the toe part 8 of the illustrated cover strip is relatively straight and of uniform width but the heel part 10 increases rapidly in width from one end toward its center portion and is of reduced width toward its other end. The curvature of the heel part also is abrupt so that a substantial widthwise force must be applied to the heel part to bring its edge into register with those of

the upper and sock lining in a shoe. To facilitate presenting the toe part to the sewing point, it is attached temporarily to the heel part 8 by a short seam 264 extending close to the edge of the strip parts to be sewed to the shoe. If the toe part 8 of the wrapper strip accordingly is led into the machine first, the heel part is carried along afterwards into the sewing point by the attaching seam 264.

The wrapper strip guide of the machine comprises a chute 266 formed by folding the edges of a width of sheet material toward each other with sufficient space between them to receive the double thickness at the overlapping attached ends of the wrapper strip parts included in the seam 264. The chute extends upwardly from a location just ahead of the sewing point in the machine in an almost vertical direction, being inclined somewhat forwardly of the machine. The folded over portion of the chute is cut away at 268 along its central section and the upper end of one side has secured to it a rearwardly curved apron 270 for insuring entry of a wrapper strip into the chute. The rearward side of the chute is secured to the lower edge of an inclined flanged tray 272 supported at its rearward end on a post 274 mounted on a table 278 to which the frame of the machine is bolted. The inclination of the tray 272 is approximately twenty degrees from the horizontal and the angle between the tray and the chute is approximately ninety degrees so that the inclination of the chute is downwardly and about twenty degrees in the direction of the work feed in the machine while that of the tray is downwardly and in a direction opposite to that of the feed.

The chute is fixed to the upper end of a frame 276 secured to the machine frame. The connection between the chute and the frame 276 comprises a slide member 280 on the chute entering into a cooperating guideway 282 on the frame 276. The guideway 282 has passing through it a clamp screw 284 loosening of which permits the chute to be shifted on the frame 276 to provide suitable adjustment for the chute toward and from the sewing point. Lateral adjustment of the chute is provided for by shifting the guideway 282 on the frame 276 through a clamp screw 286 passing through a slot in the guideway into threaded engagement with the frame 276.

The arrangement of the chute 266 and the tray 272 is such that a wrapper strip may be directed toward the sewing point in the machine either by inserting the toe part 8 of the strip first or by inserting the heel part 10 first. Whichever part of the wrapper strip is inserted first the other part will lie in flattened relation along the tray until it also is drawn into the sewing point. As illustrated in Figs. 1 and 2, the heel part 10 is shown being sewn to the shoe before the toe part of the wrapper strip. This arrangement is in accordance with the method of making platform shoes comprising the present invention.

The tray 272 which supports the trailing end of the wrapper strip is of increasing width along its length to accommodate the swinging movements of the wrapper strip at an angle to the direction of movement of the strip as the shoe is fed through the machine, the trailing end at the toe part end of the strip swinging laterally through the greatest distance as the strip is first presented to the sewing point. The tray accordingly is made with substantially greater width than the total spread of the wrapper strip 8, 10 between the outwardly curved edge thereof and a line connecting the ends of the strip.

To enable an operator to guide a variable width curved edge wrapper strip to the sewing point in the illustrated machine and to maintain the edge of the wrapper strip constantly in alignment with the point of needle operation at the sewing point, the rearward portion of the chute 266 has an opening 288 (see Fig. 3) through which projects the roughened edge of a feed wheel 289 disposed at an angle to the direction of movement of the strip in the chute and inclined toward the fold in the sheet metal comprising the chute. The angle of the

wheel 289 is such that it constantly draws the edge of the wrapper strip toward a lower folded edge portion 290 (Fig. 1) at the end of the chute which acts as a guide for the strip. If the chute is properly aligned with the sewing point, the wheel 289 will maintain the wrapper strip uniformly at the desired position for effective sewing. The opening 268 in the folded edge of the chute enables the convex curvature of the wrapper strip to bulge without being displaced at its trailing end excessively across the tray 272.

If the temporary strip attaching seam 264 and the different permanent seams 14 and 23 connecting the strip with the other shoe parts are all inserted with the same margin, there is likelihood that the later inserted seams may damage the earlier one 14 or 264. Also, if the earlier inserted seams 14 and 264 have a wider margin on the edge of the parts than the later inserted seam 23, then the earlier inserted seams will be exposed and present an unsightly appearance when the wrapper strip is carried about the edge of the platform sole into lasted relation thereto.

To prevent the threads of the earlier inserted seams 14 and 264 from being exposed to view after the wrapper strip is lasted over the platform sole or damaged by the later inserted seam 23, the temporary attaching seam 264 is inserted in the wrapper strip parts with a margin less than that provided along the final seam 23 which connects the wrapper strip permanently to the other shoe parts. For a similar reason, the seam 14 connecting the upper to the sock lining along the right forepart of the shoe is inserted with a margin, less than that provided along the final seam 23 connecting the wrapper strip to the other shoe parts (see Fig. 26). In this way the final seam 23 connecting the wrapper strip is formed inside the other seams so that when the wrapper strip is lasted over the edge of the platform sole the other seams are hidden from view within the rabbet of the platform sole.

To enable the margin of the seam inserted by the machine to be changed readily during sewing operations, the work support 24 carries beneath its work engaging surface an edge gage 291 (Fig. 3) in the form of a fin fixed at right angles to a pin 292 rotatable in the shank of the work support and in a lug 293 secured to the under surface of the work support. The outer end of the pin 292 is formed with a right angle bend to provide a convenient handle with which to rotate it. When the gage 291 is in upright position, as in Figs. 5 and 7, it engages the outer edge of the platform sole to hold it closer to the line of the seam inserted by the needle than is determined by the spacing of the rabbet gages 38 and 58. The seam connecting the right forepart of a shoe to the sock lining without the wrapper, accordingly, is inserted with the gage 291 in its vertical position.

As soon as the shank of the shoe being sewn is reached and the wrapper strip is led into the seam, the edge gage is shifted to a horizontal position out of engagement with the sole edge. The sole then is moved by the operator further into the machine until the setback surface of the rabbet of the sole enters into contact with the rabbet gages. The edge gage 291 is located to enable variations of seam margin along the platform sole of from $\frac{1}{2}$ " to $\frac{1}{16}$ " so that when the shoe is completely sewn the final seam connecting the upper and sock lining will lie a corresponding distance inside any other seam temporarily connecting the other shoe parts.

The shift of the edge gage 291 may be accomplished conveniently during sewing operations merely by a flip of the operator's finger or the machine may be stopped momentarily. In some instances it may be desirable to sew the upper and sock lining together with one seam and then to apply the wrapper strip with an additional seam running completely about the shoe. With such a method of sewing the shoe parts the non-feeding rabbet gage 58 and the feeding rabbet gage 38 guide the shoe through contact with the setback surface of the rabbet in the platform sole during the final seam 23 inserted later.

Where it seems desirable to stop the sewing operation when the seam margin is to be varied or when two sewing machines are available, one of which is employed to sew the seams of narrower margins while the other is used to sew the final seam of wider margin, the non-feeding rabbet gage 58 may be provided with a flanged gage plate 294. The plate 294 extends along the front face of both the feeding and non-feeding rabbet gages and may be swung to one side, as indicated by the dot-dash lines of Fig. 8, about a hinged mounting consisting of a screw 295 passing through the flange portion of the gage plate 294 and into threaded engagement with the non-feeding rabbet gage 58. While sewing the wrapper strip to the other parts, the gage plate 294 is swung to one side, thus enabling the greatest possible margin along the seam connecting the shoe parts.

The wrapper feed wheel 289 is secured to a spindle 296 rotating in a sleeve bearing 297 projecting from a swivel block 298 (see Figs. 1 to 4, inclusive). The swivel block has two spaced bearing lugs through which an extension of the sleeve bearing 297 passes and between which is disposed a clamp collar 299 secured to the bearing. To enable the block 298 to swivel, it has projecting upwardly from it an integral pin 300 rotatable in a bracket 302 secured by a screw 304 to the frame 276. The pin 300 is arranged to enable the block 298 to rotate in a direction which causes the roughened wheel 289 to move toward and from engagement with a wrapper strip in the chute 266. For the purpose of varying the pressure of the wheel against the wrapper strip and to facilitate entry of a wrapper strip into the chute, the upper end of the pin 300 has secured to it an actuating arm 306 formed with a handle end connected to one end of a tension spring 308, the other end of which is connected to an adjusting screw 310 secured in an upturned ear of the bracket 302. The action of the spring 308 causes the block to swivel in a direction to press the roughened wheel 289 yieldingly against a wrapper strip in the chute.

To enable the roughened wheel 289 to be retracted from the chute so that a wrapper strip may be inserted and to enable the wheel to be held selectively in an operative or an inoperative position out of engagement with the wrapper strip along certain portions of the strip, the operating arm 306 is moved manually in a forward direction against the action of the spring 308 and retained in its forward position by a manually actuated latch 312 which swings about a screw 314 entering the bracket 302 and is yieldingly actuated to latching position by a leaf spring 316 also secured to the bracket 302. After a wrapper strip has been inserted in the chute with its trailing end supported by the tray 272, manual depression of a right angle flange on the latch 312 disengages the latch from the arm 306 so that the spring 308 presses the roughened wheel 289 against the wrapper strip inserted.

Where a wrapper strip 8, 10 is employed, such as that illustrated in Fig. 22, with an outer edge of extreme curvature, it has been found necessary to drive the roughened wheel 289 positively through a rotating mechanism in order to insure engagement of the wrapper strip with the lower guiding end portion 290 of the chute 266. To rotate the roughened wheel 289 the extension of the spindle 296 passing through the swivel block 298 is connected with a flexible cable 318 enclosed in a flexible sheath 320. The sheath is supported in an arm of the swivel block 298 and is fixed within a short sleeve 322 also clamped to one of the bearing portions of the swivel block. The other end of the sheath 320 is secured within the reduced end of a coupling 324 (see Fig. 4) made fast to a bearing on a reversely bent bar 326. The lower end of the bar 326 is secured to the machine frame and the upper reversely bent end has rotatable in its bearing portion a rod 328 at one end of which is secured the driven end of the flexible cable 318. The arrangement is such that when the rod 328 is rotated the wheel 289

acts to drive the wrapper strip in the chute 266 against the lower guiding end portion 290 of the chute regardless of the curvature of the wrapper strip, thus insuring proper register of the wrapper strip with the other parts of the shoe being sewn at the sewing point.

To avoid unnecessarily abrading and overfeeding of the wrapper strip by the wheel 289, the rod 328 is driven through a frictional slip clutch connection with the main sewing shaft of the machine. For this purpose the rod 328 has rotatably mounted on its central portion a gear 330 engaging at one side of its hub a friction clutch washer 332 backed by a collar 333 pinned to the rod 328. The other side of the hub on the gear 330 is engaged by a washer 334 against which a spring 336 is compressed by a thimble 338, which thimble is in turn acted upon by an adjusting thumb screw 340 carried by the upper end of a lever 342 fulcrumed on a shoulder screw 344 threaded into a bracket 346 supported by the bar 326. The compression of the spring 336 determines the driving force applied by the gear 330 of the slip clutch to the rod 328 and consequently the driving force of the roughened wheel 289.

Where wrapper strip heel parts formed with extreme curvatures are operated upon it is sometimes necessary to vary the driving force of the roughened wheel 289 in order that the outer edge of the wrapper strip heel part may be held with certainty against the edge guiding portion 290 of the chute 266. To increase or decrease the driving force of the wheel 289, the compression of the spring 336 may be varied while sewing operations are in progress. For this purpose the lower end of the lever 342 carries a stud 347 entering loosely into engagement with the slotted end of a bell crank 348 rotatable on a pin 350 carried by the bracket 346. A rearwardly projecting arm of the bell crank 348 has connected to it a vertical link 352 also connected to the armature 354 of an electro-magnet 356 mounted at the rear of the machine on the table 278. Circuit connections for the electro-magnet include wires 358 and are carried toward the front of the machine. The circuit connections are controlled at the front of the machine by means of a toggle switch 360 having a conveniently located operating handle 362 just below the sewing point of the machine. The location of the switch handle 362 is arranged close to the sewing point so that the operator, in presenting the shoe parts to the machine, may engage the handle and operate the switch merely by a movement of his wrist or forearm.

For driving the roughened wheel rotating gear 330 its teeth mesh with those of an idler 364 rotating on a stud 366 mounted in the bar 326 and the idler engages a spur gear 368 secured to a continuation of the horizontal shaft 160 supported at its outer end in a bearing formed in the bar 326. The train of gears between the shaft 160 and the rod 328 have such a ratio that the roughened wheel 289 may be driven at a speed in excess of requirements. Under all circumstances the speed of rotation of the roughened wheel 289, however, is reduced by the resistance met in feeding the wrapper strip and the difference between its actual speed and the speed at which it is possible to drive it being taken up by slippage between the gear 330 and the friction washer 332.

Certain features of the invention herein disclosed form the subject-matter of divisional applications as follows: Serial No. 400,966, filed December 29, 1953, relating to a method of making platform shoes; Serial No. 565,956, filed February 16, 1956, relating to an improved needle guide for a sewing machine; and Serial No. 569,453, filed March 5, 1956, relating to needle reinforcing devices and wrapper strip supporting and feeding means.

Having described the invention, what I claim as new and desire to secure by Letters Patent of the United States is:

1. A shoe machine adapted for sewing an upper to a sock lining attached to the inner surface of a platform

sole, the inner edge of which beneath the sock lining is rabbeted, having stitch forming devices including a curved needle and a work support disposed with its work engaging surface at an angle to that part of the needle path along which the needle engages the work to cause the needle to enter the upper and sock lining and to emerge adjacent to the edge of the sole through the rabbet, in combination with means for securing and feeding the work comprising a non-feeding clamp and a feeding clamp, each of which includes a presser foot and a gage member having its extremity disposed between the corresponding presser foot and the work support to fit within the rabbet of the platform sole beneath the upper and sock lining, the work feeding clamp being actuated relatively to the non-feeding clamp to transfer the point of operation along the margins of the upper and sock lining.

2. A shoe machine adapted for sewing an upper to a sock lining attached to the inner surface of a platform sole, the inner edge of which beneath the sock lining is rabbeted, having stitch forming devices including a curved needle and a work support disposed with its work engaging surface at an angle to that part of the needle path along which the needle engages the work to cause the needle to enter the upper and sock lining and to emerge adjacent to the edge of the sole through the rabbet, in combination with means for securing and feeding the work comprising a non-feeding clamp and a feeding clamp, each of which includes a presser foot and a gage member having its extremity disposed between the corresponding presser foot and the work support to fit within the rabbet of the platform sole beneath the upper and sock lining, a carrier for the work feeding clamp, and a needle supporting stud on the carrier, the gage member on the feeding clamp having a needle reinforcing surface past which the needle operates during its work penetrating stroke.

3. A shoe machine adapted for sewing an upper to a sock lining attached to the inner surface of a platform sole, the inner edge of which beneath the sock lining is rabbeted, having stitch forming devices including a curved needle and a work support disposed with its work engaging surface at an angle to that part of the needle path along which the needle engages the work to cause the needle to enter the upper and sock lining and to emerge adjacent to the edge of the sole through the rabbet, in combination with means for securing and feeding the work comprising a non-feeding clamp and a feeding clamp, each of which includes a presser foot, a carrier for the feeding clamp, a needle supporting stud on the carrier, a needle guide on the carrier at the presser foot side of the work through which guide the needle moves during its work penetrating stroke, a needle reinforcing member arranged to engage with the needle at the side of the work opposite the presser feet during the work penetrating stroke of the needle, and a mounting for the needle reinforcing member on the carrier.

4. A shoe machine adapted for sewing an upper to a sock lining attached to the inner surface of a platform sole, the inner edge of which beneath the sock lining is rabbeted, having stitch forming devices including a curved needle and a work support disposed with its work engaging surface at an angle to that part of the needle path along which the needle engages the work to cause the needle to enter the upper and sock lining and to emerge adjacent to the edge of the sole through the rabbet, in combination with means for securing and feeding the work comprising a non-feeding clamp and a feeding clamp, each of which includes a presser foot, a carrier for the feeding clamp, a needle supporting stud on the carrier, a loop spreader acting to transfer each loop of thread carried by the needle through the work to others of the stitch forming devices, and a surface on the loop spreader engaging the needle during its work penetrating stroke to reinforce the needle against flexure as the feeding clamp moves the work.

5. A shoe machine adapted for sewing an upper to a sock lining attached to the inner surface of a platform sole, the inner edge of which beneath the sock lining is rabbeted, having stitch forming devices including a curved needle and a work support disposed with its work engaging surface at an angle to that part of the needle path along which the needle engages the work to cause the needle to enter the upper and sock lining and to emerge adjacent to the edge of the sole through the rabbet, in combination with means for securing and feeding the work comprising a non-feeding clamp and a feeding clamp, each of which includes a presser foot, a carrier for the work feeding clamp, a needle supporting stud on the carrier, a gage member on the feeding clamp opposite the side of the work from which the needle enters having a needle reinforcing surface past which the needle operates during its work penetrating stroke, and a needle reinforcing member arranged to engage with the needle at the side of the work with the gage member and at the side of the needle opposite the reinforcing surface on the gage member.

6. A machine adapted for sewing an upper to a sock lining attached to the inner surface of a platform sole, the inner edge portion of which beneath the sock lining is rabbeted to expose the margin of the sock lining beyond the setback surface of the rabbet, having a curved needle, a work clamping presser foot, a work support disposed with its work engaging surface at an angle to that part of the needle path between the work support and the presser foot to cause the needle to enter the upper and sock lining and to emerge adjacent to the edge of the sole through the rabbet, and a gage having its extremity disposed between the presser foot and the work support to fit within the rabbet of the platform sole beneath the upper and sock lining at a position to support the sock lining against the thrust of the needle, in combination with mechanism for imparting movement to the presser foot and rabbet gage along the line of the seam inserted to feed the work while the work support remains stationary.

7. A machine adapted for sewing an upper to a sock lining attached to the inner surface of a platform sole, the inner edge portion of which beneath the sock lining is rabbeted to expose the margin of the sock lining beyond the setback surface of the rabbet, having a curved needle, a work clamping presser foot, a work support disposed with its work engaging surface at an angle to that part of the needle path between the work support and the presser foot to cause the needle to enter the upper and sock lining and to emerge adjacent to the edge of the sole through the rabbet, a gage having its extremity disposed between the presser foot and the work support to fit within the rabbet of the platform sole beneath the upper and sock lining at a position to support the sock lining against the thrust of the needle, in combination with mechanism for imparting movement to the presser foot and rabbet gage along the line of the seam inserted to feed the work while the work support remains stationary, and supplementary clamping members comprising a non-feeding presser foot and a non-feeding rabbet gage against which the sock lining is clamped by the non-feeding presser foot.

8. A machine adapted for sewing an upper to a sock lining attached to the inner surface of a platform sole, the inner edge portion of which beneath the sock lining is rabbeted to expose the margin of the sock lining beyond the setback surface of the rabbet, having a curved needle, a work clamping presser foot, a work support disposed with its work engaging surface at an angle to that part of the needle path between the work support and the presser foot to cause the needle to enter the upper and sock lining and to emerge adjacent to the edge of the sole through the rabbet, a gage having its extremity disposed between the presser foot and the work support to fit within the rabbet of the platform sole beneath the upper and sock lining

at a position to support the sock lining against the thrust of the needle, in combination with mechanism for imparting movement to the presser foot and rabbet gage along the line of the seam inserted to feed the work while the work support remains stationary, supplementary clamping members comprising a non-feeding presser foot and a non-feeding rabbet gage against which the sock lining is clamped by the non-feeding presser foot, and mechanism for actuating both the feeding and the non-feeding presser feet including a single rocking member and connections between said member and the presser feet disposed to lift the presser feet alternately upon movement of said member in opposite directions.

9. A machine adapted for sewing an upper to a sock lining attached to the inner surface of a platform sole, the inner edge portion of which beneath the sock lining is rabbeted to expose the margin of the sock lining beyond the setback surface of the rabbet, having a curved needle, a work clamping presser foot, a work support disposed with its work engaging surface at an angle to that part of the needle path between the work support and the presser foot to cause the needle to enter the upper and sock lining and to emerge adjacent to the edge of the sole through the rabbet, a gage having its extremity disposed between the presser foot and the work support to fit within the rabbet of the platform sole beneath the upper and sock lining at a position to support the sock lining against the thrust of the needle, in combination with a carrier on which the needle, presser foot and rabbet gage are mounted, movable along the line of the seam inserted to feed the work, and mechanism for actuating the carrier to feed the work while the needle engages the work and the presser foot clamps the work.

10. A machine adapted for sewing an upper to a sock lining attached to the inner surface of a platform sole, the inner edge portion of which beneath the sock lining is rabbeted to expose the margin of the sock lining beyond the setback surface of the rabbet, having a curved needle, a work clamping presser foot, a work support disposed with its work engaging surface at an angle to that part of the needle path between the work support and the presser foot to cause the needle to enter the upper and sock lining and to emerge adjacent to the edge of the sole through the rabbet, a gage having its extremity disposed between the presser foot and the work support to fit within the rabbet of the platform sole beneath the upper and sock lining at a position to support the sock lining against the thrust of the needle, in combination with a carrier on which the needle, presser foot and rabbet gage are mounted, movable along the line of the seam inserted to feed the work, supplementary clamping members comprising a non-feeding presser foot and a non-feeding rabbet gage, and mechanism for actuating the carrier to feed the work while the needle and the feeding presser foot engage the work and while the non-feeding presser foot disengages the work.

11. A machine adapted for sewing an upper to a sock lining attached to the inner surface of a platform sole, the inner edge portion of which beneath the sock lining is rabbeted to expose the margin of the sock lining beyond the setback surface of the rabbet, having a curved needle, a work clamping presser foot, a work support disposed with its work engaging surface at an angle to that part of the needle path between the work support and the presser foot to cause the needle to enter the upper and sock lining and to emerge adjacent to the edge of the sole through the rabbet, a gage having its extremity disposed between the presser foot and the work support to fit within the rabbet of the platform sole beneath the upper and sock lining at a position to support the sock lining against the thrust of the needle, in combination with a carrier on which the needle, presser foot and rabbet gage are mounted, movable along the line of the seam inserted to feed the work, supplementary clamping members comprising a non-feeding presser foot and a non-feeding rabbet gage,

and mechanism for actuating both the presser feet including a single rocking member and connections between said member and the respective presser feet disposed to lift the presser feet alternately upon movement of said member in opposite directions.
